UNITED STATES PATENT OFFICE.

GEORGE D. HAINES, OF CHICAGO, ILLINOIS, ASSIGNEE TO VAUGHAN & BUSHNELL MANUFACTURING COMPANY, OF CHICAGO, ILLINOIS, A CORPORATION OF ILLINOIS.

TOOL-HANDLE-HOLDING MEANS.

Application filed February 8, 1922. Serial No. 534,864.

To all whom it may concern:

Be it known that I, GEORGE D. HAINES, a citizen of the United States, and a resident of Chicago, in the county of Cook and State of Illinois, have invented certain new and useful Improvements in Tool-Handle-Holding Means, of which the following is a specification.

My invention relates to means for holding handles upon the heads respectively of a large variety of hand tools such as hammers, hatchets, axes, etc., each having an eye into which the handle projects.

The usual practice in securing the handle in the eye of the tool head is to drive several filler pieces, usually of sharpened flat metal, into the end of the handle where it lies flush with the head at the eye thereof, thus spreading the wood of the handle and binding it in the eye. That method, while cheap, is not satisfactory, for when the wood dries out the further driving in of the filler pieces has little if any effect in further spreading the wood, these filler pieces having substantially no wedging action except at the entering end. If made typically wedge-like they readily work out of place, and the addition of teeth or ribs upon them does not overcome this fault. In such case the usual practice of the user is to drive in more metal, most frequently nails, in an effort to tighten the handle in the eye, the handle thus becoming much weakened, and the desired result is not attained for want of a goodly quantity of firm and strong wood in the eye.

The present invention is an improvement upon the invention of Alexander S. Vaughan, as shown by his Patent No. 1,399,401 of December 6th, 1921. Its chief object is to provide means for securing the handle in the eye of the tool head whereby the handle will be held with unusual firmness and rigidity, whereby the handle-securing means are themselves held firmly and strongly against retraction, and whereby the desired tightness of the fit between the handle and the tool head may be restored in a simple and convenient way from time to time as the drying out and shrinking of the

wood takes place. Other objects and advantages will appear hereinafter.

In the accompanying drawings, which form a part of this specification, Figure 1 is a medial vertical section through a hammer head and fragment of the handle secured together by my improved locking device; Fig. 2 is a horizontal section on the line 2—2 of Fig. 1, parts being shown in full face view; Fig. 3 is an end view showing the handle prepared to receive the locking device; Fig. 4 is an end view showing the several elements in their final position locking the handle and head together; Figs. 5 and 6 are respectively edge and face views of the wedge; Figs. 7 and 8 are respectively top and bottom views of the two pressure-transmitting members face to face; Figs. 9 and 11 are opposite side edge views and Fig. 10 is an inner face view of one of the members shown in Figs. 7 and 8.

My improved construction is herewith illustrated in connection with a hammer of well-known form. The head 10 has the usual form of eye commonly known as an adze eye, consisting of two principal parts. The first part extends from the handle-entrance opening at 11 to about the line A—B. It is defined by flat side and end walls on slanting lines and the opposite walls come closer together toward the line A—B forming wedging surfaces against which the handle 12 is driven tightly. The second part of the eye extends from about the line A—B to the outer surface 13 of the head, the eye gradually enlarging outwardly. The eye is thus provided with a constricted or throat portion, and that part of the handle 12 which passes beyond the throat at A—B is necessarily considerably smaller in cross measurements than is the eye there, leaving considerable space all around this end portion of the handle. The desideration is to fill up this space, and in such a way that the handle end is substantially provided with a head or enlarged portion which will not pass back through the throat at A—B when the tool is normally being used. The driving in of the filler pieces hereinabove mentioned accomplishes the result to a limited

extent, but with numerous disadvantages including those pointed out.

My improved locking elements illustrated consist of a pair of relatively long blunted metallic blocks, anchors or pressure-transmitting members 15—15 which are of substantially semi-cylindrical outer contour, their length being such as to reach to a place near the eye throat A—B, each therefore of having a pair of crosswise ridges 17 on its curved or cylindrical side one of which is at the lower end of each block to provide a relatively wide base. These members 15 have a width which is less than the width 15 of the eye near the throat at A—B and are therefore of considerably less width than is the opening at the outer surface 13 of the head.

The two rigid blocks or pressure-transmitting members 15 are shown as being alike in every respect and a description of one of them will be made in view of Figs. 7 to 11 inclusive. It will be noted that opposite the convex, rounded, or substantially semi-cylindrical-shaped side 18 there is a substantially flat general surface at 19 at the normally outer end portion of the member 15, and also two slanting surfaces, each of which is substantially half the width of the member 15, 30 each of which merges into the surface 19, and each of which is diagonally disposed with respect to the longitudinal direction of the members 15 and therefore also so diagonally disposed with respect to the longitudinal direction of the handle in the tool eye when the parts are normally assembled as in Fig. 1. One of these slanting surfaces, given the reference numeral 21, is upon a foot-like forward extension 40 22 of the block 15, and the other of these slanting surfaces, numbered 23, is formed as if by cutting back into the block on an angle corresponding to that of the surface 21 with respect to the plane of the flat surface 19. This will be clear from Fig. 11. The two members 15 will therefore perfectly 45 interfit with each other, as shown in Figs. 7 and 8, and when they are so positioned they define passageways between them, on the surfaces 19, 21 and 23, for the wedge member 25.

The wedge 25 comprises a body having its opposite side surfaces on converging lines to form a typical wedge. Its edges also converge, due to the convergence of the part of 55 the tool eye occupied by the wedge, as shown by Fig. 2. The entering end 26 of the wedge is sharpened. The thinner part of the wedge is bifurcated, as by stamping a longitudinal slot 27 therein, thus forming two 60 legs or prongs 30 adapted to traverse the facing inclined surfaces 21 and 23 respectively. The wedge 25 is preferably an iron stamping and is soft enough to permit the prongs 30 to bend without breaking. The

blocks 15 are also, in my practice, iron 65 stampings.

In the usual practice heretofore, after the handle has been driven tightly into the eye a wooden wedge is driven, in a somewhat diagonal direction, into the handle end in order 70 to force the wood against the walls 33. Such a wedge is used in my present construction also, and is shown at 34, Figs. 3 and 4. After this wedge 34 has been applied, a hole 35 (Fig. 3) preferably oblong, is bored longitudinally in the end of the handle substantially midway between its opposite sides and substantially midway between its opposite edges, the hole 35 having a depth equal to that of the anchors 15 and a transverse diameter equal to that of these members 15 at one of the ridges 17 when the blocks 15 are face to face. After a circular hole has been bored in the handle end the handle is tilted slightly in opposite directions, while the bit is 85 still in the hole, thus elongating the hole, especially at its outer end portions. These members 15 are then placed face to face and put into the hole 35 so as to rest upon the bottom thereof with their outer ends substantially flush with the surface 13 of the head.

The wedge 25 is next applied between the two expansion members 15, and by means of hammer blows is driven down substantially 95 flush with the surface 13 of the hammer, thus expanding the wood so as to compress it tightly against the end walls 40 and 41 of the eye. When the prongs 30 strike the inclined surfaces 21 and 23 of the blocks 15 100 they are forced to take the direction of these slanting surfaces and the points or edges 26 of the wedge pass beyond the blocks 15 and diagonally inwardly and laterally into the handle. The prongs 30 diverge, as well 105 shown in Fig. 1, and thus the wedge becomes firmly locked in the handle end. The expanding pressure upon the blocks 15 is greater at its outer portions than at other 110 places thereon, which provides that a well-distributed holding pressure is brought to bear throughout the extent of the blocks 15 and the wood is caused to fill up the eye in a tight and firm manner as desired.

Driving home the wedge forces the ribs 17 115 into the wood and locks the members 15 against retraction. One rib 17 is preferably placed at the bottom end of each member 15 so as to increase its base, and thus give additional surface there adapted to rest substantially flat upon the bottom wall of the hole 35 and cooperate to prevent these blocks from entering the handle to a greater extent than is desired. Additional holding means for the blocks 15 may be provided in the form 120 of interlocking teeth or ridges 38 on the wedge and 39 on the blocks.

An important feature of the present con-

struction is in the fact that when the handle dries out and shrinks and the head becomes loose upon it the original good and tight fit may be restored by simply driving the wedge 5 25 farther in between the members 15. Ordinarily driving it farther in the short distance between two adjacent teeth 38 on the wedge will restore the fit when the handle is appreciably loose. The drying out of the 10 wood naturally causes some looseness to occur between the handle and the head in the first part of the eye also and this may be overcome in the usual way, namely, by striking the free end of the handle a sharp blow 15 with a hammer, driving it farther into the eye, and thereupon the wedge 25 is simply driven in a short distance and the original tight fit is found to be restored. From Fig. 20 it will be noted that the difference in width between the wedge and the eye of the tool head allows for the driving in of the wedge a considerable distance. The amount of latitude in this direction may be varied so as to permit the wedge to be driven in still 25 farther if desired.

I contemplate as being within these improvements various changes, departures and modifications from what is herein specifically illustrated and described, and reference should be had to the appended claims 30 to determine the scope of the invention herein set forth.

I claim:

1. The combination of a tool head having 35 a handle-eye therein, a handle extending into said eye, a pair of blunt-ended rigid pressure-transmitting members extending into a hole in the handle from the end thereof at the eye, each of said pressure-transmitting members having an inner surface slantingly directed inwardly and laterally with respect to the longitudinal direction of the handle in the eye, said slanting surfaces facing each other, and a wedge between said 40 pressure-transmitting members adapted to be driven by hammer blows inwardly relative to them for forcing said members apart to bind the handle in the eye, respective portions of said wedge extending along and between said slanting surfaces and projecting 45 beyond them laterally into the handle.

2. The combination of a tool head having a handle-eye therein, a handle extending into said eye, a pair of rigid pressure-transmitting members extending into a hole in the handle from the end thereof at the eye, each of said pressure-transmitting members having a pair of inner surfaces slantingly directed with respect to the longitudinal direction of the handle in the eye, the said inner surfaces on one of said members facing inner surfaces respectively on the other member, said inner surfaces defining passageways between the facing ones thereof, said

surfaces inclining in different directions, 65 and wedge means between said pressure-transmitting members adapted to move inwardly relative to them for forcing said members apart to bind the handle in the eye, said wedge means including a pair of wedge 70 members one of which extends into and beyond one of said passageways and the other of which extends into and beyond the other of said passageways.

3. The combination of a tool head having 75 a handle-eye therein, a handle extending into said eye, a pair of blunt-ended rigid pressure-transmitting members extending into a hole in the handle from the end thereof at the eye and having their 80 outer ends substantially flush with the end of the handle, said hole providing a seat at its bottom for the blunt ends of said members to hold them substantially against further movement into the handle, a wedge 85 between said members adapted to be driven inwardly relative to them for forcing said members apart to bind the handle in the eye, said members having oppositely-disposed surfaces slanting inwardly and laterally 90 for bending a portion of the wedge so as to direct it diagonally into the handle when the wedge is driven between said members in said hole.

4. The combination of a tool head having 95 a handle-eye therein, a handle extending into said eye, a pair of relatively long rigid pressure-transmitting members extending into a hole in the handle from the end thereof at the eye and having their 100 outer ends substantially flush with the end of the handle, said members respectively having means within the handle for locking them in the handle against retraction, the bottom of said hole providing a transverse 105 seat for holding said members substantially against further inward movement, and a wedge positioned operatively between said members, each of said members having surfaces facing each other and directed slantingly with respect to the longitudinal direction of the handle in the eye and adapted 110 to bend a portion of the wedge in such slanting direction when the wedge is driven between said members, a portion of said 115 wedge being so slantingly directed and extending into the handle beyond said members.

5. A pressure-transmitting member for handle-holding means, comprising a relatively long body having a blunt end adapted to rest firmly at the bottom of a hole in a handle, said body having a rounded side surface and having a substantially flat surface opposite the rounded surface and also 120 a slanting surface opposite the rounded surface, the slanting surface being directed away from the plane of said flat surface. 125

6. A pressure-transmitting member for handle-holding means comprising a relatively long body having a blunt end adapted to rest firmly at the bottom of a hole in
5 a handle, said body having a rounded side surface and having a substantially flat surface at one end portion opposite the rounded surface thereof, another part of the body

having a pair of slanting normally inner surfaces each of which merges into said flat 10 surface and departs therefrom slantingly away in opposite directions from the plane of said flat surface, said slanting surfaces being opposite the rounded surface.

GEORGE D. HAINES.
